E. F. HATHAWAY ET AL
YARN SPOOL FOR TUBE FRAMES

Filed Nov. 5, 1926

UNITED STATES PATENT OFFICE.

EDGAR F. HATHAWAY, OF WELLESLEY, AND WALTER BIXBY, OF BOSTON, MASSACHUSETTS, ASSIGNORS TO SHAWMUT ENGINEERING COMPANY, OF BOSTON, MASSACHUSETTS, A CORPORATION OF MASSACHUSETTS.

YARN SPOOL FOR TUBE FRAMES.

Application filed November 5, 1926. Serial No. 146,425.

This invention relates to yarn spools and more particularly to the type of yarn-spools used in tube frames for weaving Axminster carpets, although the construction is applicable to other forms of yarn spools.

Heretofore it has been proposed to construct yarn-spools with end gudgeons having their inner ends reduced and threaded so as to be screwed into the wood of the spool barrel or into an inserted block or plug, the gudgeon then being locked against rotation by a transverse locking pin passing through both the gudgeon and the spool-barrel, but this construction, being subjected to continuous jarring, besides to shrinkage of the wood, allows the pin to work loose and shift out of place and drop out so that it interferes with proper winding on the yarn and ultimately ceases to function by dropping out, and thus 20 allows the gudgeon itself to work loose and become unserviceable.

Furthermore, a spool filled or partly filled with yarn can not be supplied with a new gudgeon or with a new anchoring pin, in case 25 of loss of one or both of these elements by working loose and dropping out, without removing the yarn from the spool an operation which, for practical reasons, is prohibitive.

The present invention overcomes these and 30 other troubles by providing a positive anchoring construction by which the accidental removal of the locking pin is prevented, while at the same time affording a durable and reliable threading engagement between the 35 spool and the gudgeon, not affected by the shrinkage of wood or by the weakness of threads cut in the wood. Moreover, the gudgeon may be readily removed or replaced without any disturbance of the yarn wound 40 on the spool since the transverse locking member or pin is held permanently in place but does not yield to penetrate the gudgeon, while the gudgeon, when screwed home, locks itself and also locks the anchoring pin against displacement. The construction also readily 45 permits the use of two journals of different diameter on each end of the spool to fit, respectively, the small bearing in the end brackets of the tube frames, or the larger bearings 50 in the intermediate brackets of the tube frames and allows an interlocking construction for the adjacent ends of two axially aligned spools in a multiple spool tube-frame.

These and other features of the invention will be described in the following specification and will be defined in the claims hereto annexed. 55

In the accompanying drawings we have illustrated a simple and convenient form of construction and arrangement embodying the 60 principles of this invention, in which:

Figure 1 is a front elevation of the adjacent ends of two interlocked spools with the intermediate bearing bracket or stand shown in section. 65

Figure 2 is an enlarged view of the end portion of a spool showing our improved gudgeon construction.

Figure 3 is a view somewhat similar to Figure 2, with the addition of a clamp-retaining member to the regular journal-gudgeon construction. 70

Figure 4 is an end view of the construction shown in Figure 3.

In the practice of this invention, as illustrated in the drawings, we employ a cylindrical spool-barrel 1, provided at its ends with an axial bore 1^a. For strength a metal ferrule 2 is secured snugly on the end of the barrel so as to project somewhat beyond the end to receive the hub or counter-sunk portion 3^a, of the metallic head 3, the center of which hub is perforated or bored in alignment with bore 1^a of the barrel. 75

At the inner end of this bore 1^a is inserted 80 an anchoring member in the form of an internally threaded bushing 4, fitting snugly into the bore, and having diametrically opposite holes registering with a transverse hole through the barrel to receive a transverse locking pin 5, which holds the bushing 4 against rotation and against axial displacement. The locking pin is transversely concaved, for a purpose presently to be described. 85

The journal-gudgeon has its intermediate portion fitting snugly into the bore 1^a of the barrel and its inner end is reduced and threaded to form threaded engagement with the threads on the interior of the bushing 4. The inner end of the gudgeon is preferably 100 convex and is arranged to engage or seat in the concavity formed at the medial portion of the locking pin 5. The outer end 6^b of the journal-gudgeon 6 is preferably of polygonal form, in this case being hexagonal in contour, 105 and forms a shoulder engaging the trans-

verse portion of the hub 3^a so as to draw the hub and its head tightly against the end of the spool and hold it there. The outer end of this hexagonal head 6^b is provided with 5 symmetrical notches 6^c, extending inward axially for a sufficient distance to form three projecting teeth or prongs 6^d intervening between the notches. The notches and the teeth are of the same arcuate dimensions so 10 that they may interlock in different circumferential relations with a similar gudgeon carried by the adjacent end of the companion spool of the tube-frame.

In the form shown, the gudgeon itself is 15 axially bored to receive a shouldered spring-plunger 8 which is normally pressed outward by a helical spring 9, seated in the axial bore of the gudgeon, said plunger being prevented from escaping from the bore by means of inwardly upset or swaged lips 6^e, formed by upsetting the inner edge portions of the teeth 6^d.

Surrounding the hexagonal end of the gudgeon is a larger journal member 7, formed 25 of cylindrical tubing, provided at its inner end with tongues 7^a, which are passed through registering holes in the hub 3^a of the head and swaged down or clinched thereon.

It will, therefore, be seen that the gudgeon 30 holds the head in place and thus maintains in position two coaxial or concentric journal members 7 and 8, one adapted to fit the large bearing in the intermediate stand or bracket of the tube frame, while the other is of small 35 enough diameter to fit the small bearing opening in the end bracket of the tube-frame. Since the smaller bearing is in the form of a yielding pintle it does not interfere with bringing two adjacent spool ends together 40 into interlocked relationship, as shown in Figure 1, while at the same time the pintle is available for use in the end bearing if it be desired to reverse the spool in order to reverse the pattern.

By means of a spanner wrench engaging 45 the end notches in the gudgeon, or of an ordinary spanner wrench engaging the hexagonal head, the gudgeon can be screwed home so that its inner end 6^a will not only engage the concaved portion of the locking pin, but will bind against it so firmly that the thrust acts in precisely the same way as does a lock or jamb nut to bind the thread against unscrewing. Instead of using a locking pin annularly grooved at its middle portion, as shown 50 at 5^a, we may use a straight pin as shown in Figure 3, and in that case the gudgeon is screwed home with sufficient force to bow or buckle the middle portion, engaged by the 55 end of the gudgeon, into concave form so that the pin thus concaved or buckled is positively locked against displacement or working loose, while at the same time the thrust of the pin against the end of the gudgeon serves to lock 60 the gudgeon against accidental unscrewing.

In Figure 3 we have shown an additional element in order to provide means for attaching the clamp-retaining springs, such means comprising an annular hub or ring 10 having 70 projecting prongs or hooks 10^a, to whose flat face is swaged the tongues of the larger bearing journal 7, the inner edge around the central orifice of this hub being engaged by the shoulder of the gudgeon 6 so that both the clamp-attaching member and the hub of the 75 head are pressed firmly against the end of the spool when the gudgeon is screwed home to locking position. Except for this clamp-attaching member and the use of a bowed pin instead of an annularly grooved pin, the construction is the same as that illustrated in Figure 2.

It will be seen, therefore, that the gudgeon locks itself in place beside positively locking, 80 against displacement, the pin that secures the anchoring member or bushing 4 in place, yet at the same time the gudgeon is very easily removed and replaced without disturbing the 85 yarn on the spool. There is no possibility of the locking pin working out to interfere with 90 the yarn, or dropping out so as to permit the working loose of the gudgeon.

What we claim is:

1. A yarn spool for a tube frame or the like, embracing in combination a spool-barrel having an axial bore in its end, a threaded bushing anchored in said bore by a transverse locking pin, a journal gudgeon having threaded engagement with said bushing and arranged, when screwed home, to form an interlocking engagement with the transverse pin to lock the pin against displacement transversely of the spool, and acting by the thrust against said pin to lock itself against unscrewing.

2. In a yarn spool, the combination with an axially bored spool barrel, an anchoring bushing in said bore, a transverse locking pin passed through said bushing and a journal gudgeon, said gudgeon and said pin being releasably interlocked to hold said pin and said gudgeon against accidental removal, while permitting removal of the gudgeon without removing the pin.

3. In a yarn spool, the combination with an axially bored spool barrel, an anchoring member inserted therein, a transverse locking pin, a journal gudgeon projecting into said bore and having its inner end engaging a concaved middle portion of said locking pin to prevent withdrawal of the pin, said gudgeon having an exterior shoulder adapted to engage and hold the interposed portion of a spool-head against the end of the spool.

4. In a yarn spool, the combination with a spool barrel having an axially bored end to receive a journal gudgeon, gudgeon-anchoring means located and locked inside said bore, an axial journal gudgeon having releasable threaded engagement with said anchor-

ing means and acting, when screwed home, to anchor both itself and its anchoring means from working loose.

5. In a yarn spool, the combination with a barrel having an axial end bore, gudgeon-retaining means secured therein, a self-locking journal-gudgeon releasably engaged with its retaining means, the outer end of said gudgeon being provided with two concentric bearing journals of different diameter, arranged one inside of the other, the inner one being retractile under endwise pressure.

6. In a yarn spool, the combination with a spool-barrel having an axial bore in its end, an internally threaded bushing inserted in

said bore, a transverse locking pin passed through said barrel and said bushing, an axial gudgeon having an inwardly projecting extension having threaded engagement with said bushing and arranged to engage a concaved portion of the locking pin when screwed home, the outer end of said gudgeon containing a spring-pressed pintle adapted to form a retractile journal, and being formed to hold a spool-head firmly against the end of the spool.

In witness whereof, we have subscribed the above specification.

EDGAR F. HATHAWAY.
WALTER BIXBY.
